UNITED STATES PATENT OFFICE

RUSSELL B. KINGMAN, OF ORANGE, NEW JERSEY, ASSIGNOR TO METAL TEXTILE CORPORATION, A CORPORATION OF DELAWARE

DESIGN FOR A FINGER PIECE FOR SCOURING PADS

Application filed October 31, 1931. Serial No. 41,585. Term of patent 14 years.

To all whom it may concern:

Be it known that I, RUSSELL B. KINGMAN, a citizen of the United States, residing at Orange, in the county of Essex and State of New Jersey, have invented a new, original, and ornamental Design for Finger Piece for Scouring Pads, of which the following is a specification, reference being had to the accompanying drawings, forming part thereof.

In said drawings, Fig. 1 is a front face view, Fig. 2 is a side edge view and Fig. 3 is a top or plan view of a finger piece for scouring pads, showing my new design.

I claim:

The ornamental design for a finger piece for scouring pads, as shown.

RUSSELL B. KINGMAN.
